TIERED PARTS BIN

William D. Taylor, Wooster, Ohio, assignor to Rubber-maid Incorporated, Wooster, Ohio, a corporation of Ohio

Filed Mar. 27, 1967, Ser. No. 6,386

Term of patent 14 years

(Cl. D87—1)

FIG. 1

FIG. 2

FIG. 3

FIG. 1 is a perspective view of a tiered parts bin embodying my new design.

FIG. 2 is a top plan view thereof.

FIG. 3 is a side elevational view thereof.

As shown in FIG. 1, the middle tray is identical to the top tray but turned 90° thereto, and the bottom tray is the same as the middle tray except for certain changes in compartment details. Thus, while the half circle area to the right of the center diametrical divider in the bottom tray is the same as the half circle area to the right of the center divider in the middle tray, the half circle area to the left of the center divider in the bottom tray differs from the half circle area to the left in the middle tray in that in the bottom tray the dividers to the left of and parallel to the center divider are omitted and the transverse dividers are extended to the right to intersect with the center divider.

As indicated in FIG. 3, the bottom tray is supported on a circular ball bearing raceway having a flat planar bottom surface and an upper rim flange attached to the

bottom tray only by circumferentially spaced angular lugs depending from the bottom tray and engaging under said flange.

I claim:

The ornamental design for a tiered parts bin, as shown and described.
